VERNIER DRIVE MECHANISM

Stanley S. Cramer, Haddon Heights, N. J., assignor to Radio Condenser Company, Camden, N. J.

Application June 2, 1934, Serial No. 728,651

6 Claims. (Cl. 74—10)

This invention relates to a vernier drive mechanism especially useful in connection with variable condensers used in the tuning circuit of a radio receiving set, although it may be applied to other electrical devices where coarse and fine circuit adjustments need to be made.

Before the advent of the gang condenser, that is to say, a plurality of condenser units mounted in the same frame, the fine adjustment was usually obtained by a vernier plate which would be set to slightly vary the capacity after the coarse adjustment had been made by the regular tuning knob. However, the use of a separate vernier plate and adjusting means in a gang condenser makes the same complicated and expensive.

It is therefore the object of my present invention to be able to obtain both the coarse and fine adjustment of the adjustable portion of the condenser, such as the rotor, in a relatively simple and inexpensive manner.

A further object of my invention is to provide a fine adjustment such that persons who do not have a sensitive touch can obtain the necessary fine adjustment without difficulty.

My present invention will be readily understood by reference to the annexed drawing, wherein:

Figure 1 shows a side elevation of a two-gang condenser with my improvement applied thereto.

Figure 2 is a view of the right-hand end of the gang condenser shown in Figure 1.

Figure 3 is a horizontal section on the line 3—3 of Figure 2 on an enlarged scale.

Figure 4 is a vertical section on the line 4—4 of Figure 2, on an enlarged scale.

Figure 5 is a section on the line 5—5 of Figures 1 and 3 on an enlarged scale.

Figure 6 is a view similar to Figure 3 but of a modified form showing, in addition, the actuating devices attached to the operating shaft.

In the several views of the drawing, wherein like numbers refer to corresponding parts 1, and 2 are the end bearing plates of a two-gang condenser. The rotor shaft 3 is supported by a ball bearing 4 in the end plate 1 in the manner such as disclosed in my Patent 1,800,719 issued April 14, 1931. The bearing 5 in the rear end plate 2 may be of the same type, but as illustrated, it comprises a single ball-and-socket bearing. Each of the stators 6 is carried on an insulator 7 fastened to the frame in any satisfactory manner as by rivets 8.

The rotor or main shaft 3 has a projection 9 extending beyond the end bearing plate 1. The

extension 9 has a bore 10 terminating in an annular shoulder 11 beyond which a smaller bore 12 is provided. Passing through the shaft extension 9 into the bore 12, is a plurality of holes to receive balls 13, three being shown in Figure 5. Preferably the holes for the balls 13 are smaller in diameter than the diameter of the balls so that the shaft 9 acts as a ball retainer whereby, in assembly operations, when the balls are dropped through the bores 10 and 12, they may be readily inserted in place as shown in several figures, that is to say, when the vernier shaft 14 is inserted into the hollow portion of the shaft 9, the inner end of the shaft 14 forces the balls 13 into the holes made to receive them in the outer shaft 9, while the inner end of the vernier shaft 14 is provided with a ball-race 15 which is engaged by the balls 13. The vernier drive is completed by a cap 16 made of highly resilient material and, as best shown in Figure 2, is provided with two arms or lugs 17 which preferably extend from diametrically opposite sides of the cap 16. Each of the lugs 17 has projections 18 formed therein to act as positioning means for sockets 19 formed in each of the arms 20 carried by the spring-retaining member 21 that is fastened to the end bearing plate 1 in any satisfactory manner as by a screw 22.

The cap 16 is so formed that the socket portion 23 thereof engages the balls 13 in such a manner as to press these balls against the sides of the raceway 15 of the vernier shaft 14, as well as against the walls of the holes in the main shaft 9. Furthermore, the cap 16 is so formed that it does not engage the end plate 1, a clearance space 24 being left so as to allow for further adjustment of the cap 16 by the screw 22 and the adjustable tensioning member 21.

The shaft extension 9 is provided with any satisfactory operating device, such as a knob 25, which may be fastened thereto by set screw 26; also, the vernier shaft 14 is provided with a suitable operating device such as a knob 27 fastened thereto by a set screw 28 engaging a flat surface 29 on the shaft 14. By operating the knob 25 on the shaft 9, a direct adjustment is made of the rotor plates carried by the shaft 3 to get a coarse adjustment of the condenser. By turning the knob 27, the vernier shaft 14 is operated and through the reduction provided through the medium of the balls 13, the raceway 15 and the frictional engagement of the shaft 9 through the cap 16 as described, the shaft 3 will be slowly turned at a reduction of speed 35

over the knob 27, depending on the relation of the ball races with respect to each other.

In Figure 6 the cap 16 is made somewhat differently from the cap heretofore described, in that it has two projecting arms 30 and 31 arranged diametrically opposite each other and fastened directly to the end plate 1 by screws 32. While a certain amount of adjustment can be obtained, as will be seen by reference to Figure 6, with this form of cap, I prefer the construction heretofore described. In addition, the vernier shaft 14 is made somewhat differently in Figure 6 than in the other figures, but in general this construction functions in about the same manner as in the preferred form previously described.

What I claim is:

1. A vernier drive mechanism including a single piece main shaft hollow only for a short distance at the drive end and a vernier shaft 20 journaled within the hollow end of the main shaft and having a raceway formed therein near the inner end thereof, a support member for the main shaft, said main shaft having holes entering the hollow end thereof, balls positioned in said 25 raceway and protruding through said holes in the main shaft which acts as a ball retainer, a resilient cap fitting over said balls and engaging them for the purposes described, and means for adjustably mounting said cap on the outer part 30 of said support member in operative position over said balls.

2. A vernier drive mechanism as set forth in claim 1, characterized in that the inner wall of the cap engages said balls without the cap coming in contact with the support member, and further characterized in that said means comprises a spring member carried by said support

member that holds the cap in working position over the balls.

3. A vernier drive mechanism as set forth in claim 1, characterized in that the inner wall of the cap engages said balls without the cap coming in contact with the support member, and further characterized in that the cap has a plurality of lugs disposed so pressure may be applied uniformly to the cap, said lugs having positioning means thereon, and further characterized in that said adjustable means comprises a member having resilient arms to engage said lugs to apply pressure thereto which is carried by said support member, said arms having means to cooperate with said positioning means on said lugs.

4. A vernier drive mechanism as set forth in claim 1 characterized in that said means comprises a resilient member fastened to said support member.

5. A vernier drive mechanism comprising a pair of shafts one journaled within the drive end only of the other, a bearing support for the last-mentioned shaft end, the last mentioned shaft end having holes therein to form a cage for balls, balls seated in the cage and engaging the end of the inner shaft and protruding through said holes, and a reaction means for said balls consisting of a cap resiliently held in position over said balls and acting as a housing therefor to cause them to transmit motion from the inner shaft to the outer shaft.

6. A vernier drive mechanism as set forth in claim 5, further characterized in that the inner shaft end has a formation such that it is held in place by the balls against removal, as soon as the cap is held in operative position.

STANLEY S. CRAMER.
